United States Patent Office.

HIRAM SLOOP, OF MOUNT HEALTHY, ASSIGNOR TO HIMSELF AND JEPHTA GARRARD, OF CINCINNATI, OHIO.

Letters Patent No. 73,933, dated January 28, 1868.

IMPROVEMENT IN HILL-SIDE PLOUGHS.

The Schedule referred to in these Letters Patent and making part of the same.

TO WHOM IT MAY CONCERN:

Be it known that I, HIRAM SLOOP, of Mount Healthy, Hamilton county, Ohio, have invented a certain new and useful Hill-Side Plough; and do hereby declare the following to be a full, clear, and exact description thereof, reference being had to the accompanying drawing, making part of this specification.

My invention relates to the class of hill-side ploughs which are susceptible of adjustment for alternate right and left-hand ploughing in succession, and is so arranged that the reversal is effected by the simple act of swinging the beam without disturbing the plough in the furrow.

Figure 1 is a perspective view of my plough, in position for right-hand ploughing, except that the beam is unlocked.

Figure 2 is a side elevation, showing the beam in position for left-hand ploughing, and firmly locked to the plough proper.

Figure 3 is a top view thereof, the beam being released and partly swung around.

In the above figure portions of the stock are removed, so as to expose the working parts.

My plough proper consists of two ordinary "bar-shares," A A', right and left respectively, united back to back, so as to have their land-sides flush with each other, and their points diametrically from each other. A fish-plate, B, unites the two land-side bars to each other and to a land-side plate, C, and another fish-plate, D, attaches together the two mould-boards. Extending upward from the ploughs proper are two sheths, E E', made fast to a D-formed swivel-plate, F, connected to the under side of the beam by a strong king-bolt, G, which bolt also secures the rear end of a strap or bar, H, which, forming a loop, h, around the curved portion of the D, is attached to the under side of the beam, in front of it, and constitutes a shoulder or abutment against which the sheths alternately press, and by which, in connection with a pair of dogs, I J, suitably notched, i j, serves to hold the sheths in either position. The said dogs are pivoted to the beam at K K', and have their summits connected by rods L L' with a T-formed lever, M, accessible to the operator, and adapted to be secured in the locked position by a rack, N.

The operation is as follows: The plough having reached the end of the furrow, the lever M is discharged from the rack N and pushed to the right, so as to release the dogs I J. The beam is then swung half around and locked in its reverse position, and the team started forward on its return trip or through, without disturbing the plough proper, except to guide it into the land in the common way.

I claim herein as new, and of my invention—

A reversible hill-side plough, characterized by two ploughs proper, secured back to back, and provided with a beam capable of being swung and locked in diametrically opposite directions, dogs I J, abutment-bar H, sheths E E', lever M, and rack N, or their equivalents.

In testimony of which invention, I hereunto set my hand.
